ASH RECEPTACLE CLOSURE WITH TILTING MEANS

William C. Panzer, Chicago, Ill.

Application September 25, 1945, Serial No. 618,437

3 Claims. (Cl. 220—36)

1

This invention relates to tilting means for ash receptacle closures or the like, such as are used more particularly by tobacco smokers and with cigars and cigarettes.

Much annoyance has been caused smokers in the past by reason of the necessity of inserting a finger, or sometimes a pencil, into the bowl for the ashes, cigar stubs and cigarette butts, and such refuse, in order to tilt the closure to discharge the refuse from the hopper into the inner depository of the ash tray or smoking stand. Whether a finger or pencil be used, the operation is messy and disagreeable.

The present invention aims to provide a structure of this class embodying a tiltable closure and a tilter post carried by the closure offset from the center of the closure so as to obstruct as little as possible the area of discharge of the refuse off of the closure into the depository and to cause a minimum of obstruction to free sliding movement of the refuse from off of the closure into the depository.

These and other objects and advantages will be apparent from the following description, taken together with the accompanying drawings, of an illustrative embodiment of the invention, and in which drawings—

Figure 1 is a plan view of a structure embodying the present invention;

Figure 2 is a vertical section taken on the line 2—2 of Figure 1; and

Figure 3 is a fragmentary cross-section taken on the line 3—3 of Figure 1.

Referring in detail to the illustrative construction shown in the drawings, the numeral 10 indicates a depository for cigar, pipe, or cigarette ashes, cigar stubs, cigarette butts and such refuse, which depository may be a part of an ash tray, smoking stand or the like. Such depository is commonly provided with a cover, here represented by the numeral 11, which commonly has a somewhat ornamental skirt 12 telescoping over the upper edge of the depository 10 and a central bowl-like portion 13. The depository 10 and cover 11 are generally cylindrical and the bowl portion 13 of the cover at the center of its concavity has a central opening 14 about the margin of which the bowl portion 13 is vertically downturned as at 15.

The circular central opening 14 is usually at least partially closed by the usual tiltable disc closure 16, which is also concave on its upper face 17 and convex on its lower face 18 so as to conform somewhat with the bowl-like formation 13. The closure 16 may be carried by the por-

2

tion 13 as in this instance by integral radial lugs 19 on the closure which are loosely and rotatably received in slots 20 in the flange 15 margining the opening 14. The lugs 19, of which there are two, each received in a slot 20 at diametrically opposite sides of the closure, thus constitute pivot trunnions for rotative or tilting movements of the closure, and a plane through these lugs normal to the closure passes through the axis of rotation or tilting of the closure.

In accordance with the present invention, the closure 16 carries a tilter post 21 rigidly fixed to the closure in a position offset from the center of the closure. In this instance, the closure has an embossment 22 on its upper face adjacent the margin of the closure and on a line coincident with the axis of tilting of the closure as represented by a line connecting the pivot lugs or trunnions 19. This embossment 22 provides a platform 23 on the upper concave face of the closure and a recess 24 on its lower convex face. The post 21 adjacent its lower end desirably has a conical foot 25 which rests on the platform 23 and below this the post has an appendage or screw shank 26 which passes through a perforation 27 in the platform 23. A counterweight 28 having therein a tapped socket recess 29 is arranged to threadedly mate with the screw shank 26 and be screwed thereon into the recess 24, thus serving to secure the post 21 and counterweight 28 together and to the closure. At its upper end, the tilter post preferably has a bulbous head 30.

The tilter post 21 is desirably of a height extending from the upper face of the closure 16 approximately equal to a radius of the closure, so that when the closure is tilted, as shown in dotted lines, the tilter post 21 will, by contact with a margin of the bowl portion 13, as suggested in dotted lines in Figure 1, limit rotation or tilting of the closure so as to prevent the closure from capsizing or turning all the way over, in which case undesirably the tilter post would extend downwardly and the counterweight 28 would extend upwardly. This is prevented as shown, and when tilting pressure is relieved, the closure will normally maintain itself upright in horizontal position with its concave face uppermost and with tilter post 21 extending upwardly therefrom and the counterweight extending downwardly from the lower or convex face of the closure.

So constructed and arranged, when a mass of refuse has accumulated on the closure, the latter may be tilted to discharge the refuse into the

depository 10 by striking say the bulbous top 30 of the tilter post with the finger, or with a pencil for example, or even with the cigar, pipe, or cigarette itself, and thus causing the closure to tilt against the action of the counterbalance provided by the counterweight 28.

In this tilting of the closure, the finger, or the pencil, or the cigar, do not need to be inserted into the mass of ash, refuse or the like, reposing on the closure prior to tilting, and are therefore kept free and clean therefrom, while, at the same time, ease of tilting of the closure is enhanced without the tilter post interfering with free movement of the refuse from off of the closure into the depository and with a minimum of obstruction of the area of discharge therefrom.

The counterweight 28 represents illustrative means carried by the closure for counterbalancing the post 21 to normally maintain the closure in horizontal position with the post upstanding, and, in this instance, the counterweight 28 specifically also functions as a nut for securing the post to the closure.

The upper margin of the bowl-like cover 11 may desirably carry the usual rest pieces 31 having semi-cylindrical indentations 32 therein for resting a cigar or cigarette during intervals when it is not being smoked.

As is well known, the refuse discharge into the depository 10 may be, generally at infrequent intervals, removed therefrom when desired as for example by temporarily removing the bowl-like cover 11, carrying with it the other parts; or the refuse may be removed through a lower portion of the depository not here shown and which forms no part of the present invention.

The invention is not intended to be limited to details of construction here shown for purposes of exemplification and such changes may be made therein as fall within the scope of the appended claims without departing from the invention.

The invention having been described, what is here claimed is:

1. In a structure of the class described, the combination of a depository, a cover therefor, a tiltable closure for said cover, said closure being of concave formation and having an embossment on its upper concave face adjacent the margin of the closure and coincident with its axis of tilting, and a tilter post upstanding from said closure, said tilter post being offset from the center of said closure and located on said embossment.

2. In a structure of the class described, the combination of a depository, a cover therefor, a tiltable closure for said cover, said closure being

of concave formation and having an embossment on its upper concave face adjacent the margin of the closure and coincident with its axis of tilting, a tilter post upstanding from said closure, said tilter post being offset from the center of said closure on said embossment, and a counterweight secured on the underface of said closure in the recess provided by said embossment, a perforation in said embossment, a threaded appendage on said post passing through said perforation, a threaded socket opening in said counterweight whereby the counterweight is screwed onto the appendage to secure the post and counterweight together and to the closure, said tilter post having a conical foot abutting said embossment on the upper side of said closure, and having a bulbous head.

3. In a structure of the class described the combination of a cover element having an upwardly facing cavity therein and having an opening at the bottom thereof, a tiltable closure of upwardly facing concave formation for said opening mounted on said cover element, said closure being tiltable on a horizontal axis extending diametrically of said cover, a tilter post upstanding from said closure, said tilter post being offset from the center of said closure and adjacent the edge thereof, said post being of such height as to engage said cover on tilting movement of the closure to limit said movement, a counterweight carried by the closure upon the underface thereof directly below said post for counterbalancing said post to normally maintain the closure in horizontal position with the post upstanding, and screw means, including a threaded shank passing through an aperture in said closure, for connecting said post and counterweight and clamping them both to the closure, the closure having a flat portion from which the post upstands and through which said screw means passes.
